CLAIM

The ornamental design for a connector for coaxial cable, substantially as shown.

DESCRIPTION

FIG. 1 is a front elevational view of a connector for coaxial cable showing our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a cross-sectional view thereof, taken along line 7—7 of FIG. 1;

FIG. 8 is a perspective view thereof.
